(57) **CLAIM**

The ornamental design for a workspace power accessory, as shown and described.

DESCRIPTION

FIG. 1 is a right, top, front perspective view of a workspace power accessory embodying our new design;

FIG. 2 is a front elevational view thereof, the rear elevational view thereof being a mirror image of the front shown;

FIG. 3 is a right side elevational view thereof;

FIG. 4 is a left side elevational view thereof;

FIG. 5 is a top plan view thereof;

FIG. 6 is bottom plan view thereof;

FIG. 7 is a right, top, front perspective view of a workspace power accessory according to another embodiment of our new design;

FIG. 8 is a front elevational view thereof, the rear elevational view thereof being a mirror image of the front shown;

FIG. 9 is a right side elevational view thereof;

FIG. 10 is a top plan view thereof;

FIG. 11 is a left side elevational view thereof;

FIG. 12 is bottom plan view thereof;

FIG. 13 is a right, top, front perspective view of a workspace power accessory according to another embodiment of our new design;

FIG. 14 is a front elevational view thereof, the rear elevational view thereof being a mirror image of the front shown;

FIG. 15 is a right side elevational view thereof;

FIG. 16 is a left side elevational view thereof;

FIG. 17 is a top plan view thereof; and,

FIG. 18 is bottom plan view thereof.

The broken lines in FIGS. 2, 8 and 13-18 are included for the purpose of illustrating portions of the workspace power accessory that form no part of the claimed design.
